UNITED STATES PATENT OFFICE.

WESLEY E. COCHRAN, OF CLEVELAND, OHIO.

LIGHTING FIXTURE.

Application filed November 17, 1921. Serial No. 515,805.

To all whom it may concern:

Be it known that I, WESLEY E. COCHRAN, a citizen of the United States, residing at Cleveland, in the county of Cuyahoga and State of Ohio, have invented certain new and useful Improvements in Lighting Fixtures, of which the following is a specification.

My invention relates to improvements in lighting fixtures, and more particularly to improvements in shade or globe holders for such fixtures.

The primary object of the invention is to provide a generally improved shade holder of the class indicated which will be exceedingly simple in construction, cheap of manufacture, and efficient in use.

A further and very important object is the provision of internally arranged normally concealed adjustable shade engaging and holding fingers for use in lieu of the ordinary shade securing thumb screws now in common use, and, as contradistinguished from such thumb screws, being adapted to engage within the neck or heel portions of the shade or bowl in co-operative relation thereto and to the adjacent shade or bowl receiving portions of the body of the fixture and being so constructed, mounted and arranged as to readily receive and conform to shade or bowl necks of varying forms and contours, and being also particularly adapted to resiliently engage the parts thereby permitting the same to expand and contract with varying temperatures without any liability of breakage to the shade, bowl, or globe being held.

With the above mentioned and other ends in view, the invention consists in the novel construction, arrangement, and combination of parts, hereinafter described, illustrated in some of its embodiments in the accompanying drawings, and particularly pointed out in the appended claims.

Referring to the drawings, forming a part of this specification, Figure 1 is a side elevation of a lighting fixture embodying my improvements.

Fig. 2, a horizontal cross sectional view taken on line 2—2 of Fig. 1.

Fig. 3, an enlarged central vertical sectional view of the same.

Fig. 4, a fragmentary vertical sectional view showing a modified form of mounting actuating and adjusting the shade engaging and holding fingers.

Similar numerals of reference designate like parts throughout all the figures of the drawings.

The body of the fixture may be of any suitable and convenient form and so likewise as to the specific form or shape of the shade. In the present instance, the body or shade supporting portion of the fixture comprises a downwardly flaring housing or hood 1, terminating at its top in a reduced stem or socket receiving portion 1^a. The shade holder portion of the housing or hood 1, in the present instance, comprises an annular horizontally extending ring portion 1^b terminating in a depending annular flange 1^c, the latter, in the present instance, terminating at its lower edge in a beading 1^d, said annular or flange portions 1^b and 1^c, conjointly forming the shade or bowl receiving portions of the holder and with which the neck and heel portions of the globe or shade and the improved adjustable shade engaging and holding fingers are adapted to co-operate as hereinafter described.

The shade may be of any desired specific form and, in the present instance, is in the specific form a bowl 2, having a central opening 2^a, at its lower portion and provided at its top with a reduced or neck portion affording, in the present instance, an annular shoulder 2^b, and provided with the usual heel 2^c, forming the usual annular groove into which the conventional shade supporting screws heretofore used are adapted to fit. In the present instance, the neck of the bowl terminates in an outwardly flaring flange 2^d.

Referring now to the improved adjustable shade engaging and holding fingers to which this invention particularly relates, it will be seen that I provide a plurality of adjustable elements or fingers 3, internally arranged and normally concealed from view as will appear upon reference to Fig. 1 of the drawings.

When used in connection with a fixture of the specific form herein disclosed, the adjustable shade engaging and holding elements or fingers 3, may be arranged within the housing or hood 1, and may be secured and mounted in any suitable and convenient manner, as for example, by means of attaching elements 3^a, in the present instance, in the specific form of screw bolts and nuts. The adjustable shade engaging elements or

fingers 3, are preferably provided with horizontally extending tongue or nose portions 3^b, arranged to take under and co-operate with the annular heel portion or flange 2^c, in 5 centralizing, elevating and clamping the shade or bowl when adjusted, and in co-operation, in the present instance, with the annular flanges 1^b and 1^c, in engagement with the shoulder and flange portions 2^b and 10 2^d, of the bowl.

As a means of actuating and adjusting the shade engaging and holding elements or fingers 3, whereby the latter may be moved upwardly to engage beneath the heel 15 portion 2^c, of the bowl neck as shown in Fig. 3 of the drawings, or to move said elements or fingers inwardly to disengage the bowl or shade, or for the insertion of a shade or bowl, suitable actuating and 20 adjusting means are provided on the exterior portion of the body or shade holder of the fixture, said means, in the present instance, as shown in Figs. 1, 2 and 3 of the drawings, comprising actuating and adjusting 25 elements 4, arranged, in the present instance, on the exterior portion of the housing or hood 1, and extending inwardly through the latter and engaging with the fingers or elements 3. The elements 4 may 30 take the specific form of screw bolts threaded in threaded openings in the intermediate portions of the fingers and having heads 4^a, for adjustment by an ordinary screw driver. The shade engaging and holding elements 35 3 may be made of resilient or spring material and arranged to normally move toward and take a position corresponding to the dotted line position in Fig. 3 of the drawings when the adjusting screws 4 are 40 turned backward or given a retrograde movement. When the fingers are in such retracted position the horizontal tongue or nose members 3^b will form an intervening annular space to receive and clear the heel 45 or neck portion 2^b of the shade or bowl so that the latter may be readily placed in position whereupon the spring elements or fingers 3 are drawn outwardly, the nose portions 3^b, engaging beneath the inclined heel 50 portion of the bowl to raise the latter as well as centralize the same, bringing the annular flange and shoulder portion 2^d and 2^b, into engagement with the bowl receiving and supporting flanges 1^c and 1^b, of the 55 holder.

It will be seen that the free ends 3^b, of the shade engaging and holding elements or fingers 3, are admirably adapted to readily receive and conform to the neck or heel 60 portions of shades or bowls of varying forms and contours and that the resiliency of the elements or spring fingers 3 enables the latter to move or adjust themselves with the expansion and contraction of the adjacent 65 surrounding parts of the shade holder and

shade in accordance with varying temperatures.

In the form shown in Fig. 4 of the drawings the shade engaging and holding finger 3 is attached so as to normally move outwardly and take the dotted line position in engagement with the annular heel portion of the bowl instead of normally retracting, as shown in the form and mounting referred to in Figs. 1, 2 and 3 of the drawings. In 70 this instance, the actuating and adjusting element 4^b, acts in one direction only as distinguished from the specific screw bolt form 4, shown above and the adjusting element 4^b is in the form of a cam pivotally mounted on a pivot element 4^c, arranged on the exterior portion of the hood or housing or otherwise suitably supported on the latter, said cam acting within a slot 1^c, of the housing 1 and being adapted to be operated by 80 means of a handle or lever 4^d. When the lever 4^d is moved from the full line position to the dotted line position and the base portion of the finger 3 is relieved of the pressure of the cam head the finger 3 will 85 move outwardly into engagement with the annular heel portion 2^c of the bowl and the latter will be held by the spring action of the normally expanded finger 3 and as illustrated in dotted lines in Fig. 4 of the 90 drawings.

The term "shade" as used in the claims is understood to include any suitable form of shade and irrespective of whether in the specific form of a globe, or a bowl.

Having thus described some of the embodiments of my invention, without having attempted to set forth all the forms in which it may be made, or all the modes of its use, what I claim and desire to secure by Letters Patent is,—

1. A shade holder, including a downwardly flaring hood terminating in annular flanges forming an annular shade receiving seat, a shade bowl terminating in reduced annular outwardly inclined neck and heel portions fitted in said annular seat, interior spring elements movably arranged within and spaced from said downwardly flaring hood and terminating at their free ends in horizontal tongue portions extending within said neck portion of said shade, and means operable on the exterior of said hood for moving said spring elements radially outward and causing said tongue portions to yieldingly engage beneath said outwardly inclined heel portion thereby holding and elevating the neck portion of said shade bowl in said annular shade receiving seat under spring tension.

2. In a lighting fixture, a shade supporting holder including a downwardly flaring housing terminating at its lower edges in annular flange portions conjointly forming an annular shade seat, and a shade bowl

provided at its top with a reduced neck portion including an annular inwardly extending downwardly inclined heel and an annular external shoulder seated in said shade receiving portion of said holder, 5 spring fingers arranged within said downwardly flaring housing of said shade supporting body and having their free ends spaced from said seat and terminating in 10 horizontally extending nose portions, and means operable on the exterior portion of said holder for operating said spring fingers to permit said horizontal nose portions to engage beneath said annular downwardly inclined heel portion and centralize said 15 bowl in said holder.

In testimony whereof I have affixed my signature.

WESLEY E. COCHRAN.
